UNITED STATES PATENT OFFICE.

FREDERICK LAMPLOUGH, OF WILLESDEN, LONDON, ENGLAND.

STEAM OR OTHER FLUID PRESSURE MOTOR.

SPECIFICATION forming part of Letters Patent No. 722,722, dated March 17, 1903.

Application filed December 14, 1901. Serial No. 85,865. (No model.)

To all whom it may concern:

Be it known that I, FREDERICK LAMPLOUGH, engineer, a subject of the King of Great Britain, residing at 6 Scrubbs Lane, Cumberland Park, Willesden, in the county of London, England, have invented certain new and useful Improvements in Steam or other Fluid Pressure Motors, of which the following is a specification.

10 This invention relates to steam and other fluid pressure motors, and has for its chief object to so construct the same that they shall be light, compact, simple in construction, and very suitable for the propulsion of road-vehicles, steam-launches, and the like.

An important feature of the invention is the valve-gear, which is constructed on the well-known Joy principle, but modified in such manner that the oscillatory parts participate only in a small arc of movement, so as to permit of the gear being located or inclosed within a comparatively small chamber wherein the crank works.

Another important feature is a device for 25 operating the actuating-shaft of the valve-gear through the intervention of a screw which can be disengaged when large adjustments of said shaft are to be effected.

Another important feature is that the motor 30 is unprovided with the usual stuffing-boxes for the working parts, the only stuffing-boxes being those in which are mounted the inner ends of tubes and which serve as expansion-joints therefor, as hereinafter described.

35 In the accompanying drawings, Figure 1 is a longitudinal section of the motor for use with steam as the motive fluid. Fig. 2 is a horizontal section, and Fig. 3 an end view, of the same. Fig. 4 is a plan of the crank-chamber. Fig. 5 is a longitudinal section similar to Fig. 1, showing the parts in another position. Fig. 6 is an edge view, and Fig. 7 a face view, of the device for adjusting the position of the valve-gear.

45 A A are the working cylinders, of which there are two in the example illustrated, arranged in alinement with each other and preferably composed of steel tubes connected with the central or body portion B, that constitutes 50 the aforesaid crank-chamber. The said body portion B comprises a rectangular casing having internally-screw-threaded bosses B^X B^X to

receive the aforesaid cylinders A, which are correspondingly screw-threaded at A^X A^X to screw into said bosses. The body portion B 55 is open at the top and sides to facilitate the assembling of the parts it is destined to inclose, cover-plates B' B² B² being provided for closing the said openings. This portion B and its covers are preferably made of aluminium for sake of lightness.

c c are the valves for controlling the inlet and outlet of the steam to and from the working cylinders through the passages a a. These valves are of the piston type and work in stationary tubes a' a', which are mounted at their outer ends in steam-chests C C, having cavities c' c², the former of which communicates with the exhaust-opening a² and the latter of which communicates with the aforesaid passages a a. The inner ends of said tubes are mounted in stuffing-boxes a³ a³, with which the body portion B is provided. Instead of these stuffing-boxes (which serve as expansion-joints) I may provide the said tubes with 75 flanges and connect them to the body portion B by means of screws or otherwise. Each of the tubes is formed with ports a⁴ a⁵, the former of which communicate with the cavities c² in the steam-chests leading to the passages a and the latter of which communicate with the cavities c' in the steam-chests leading to the exhaust-opening a².

A' A' are the cylinder-end covers, which are preferably made of aluminium and secured in any appropriate manner to annular flanges A² A², also preferably of aluminium, screwed onto the outer ends of said cylinders. The steam-chests C C are also preferably made of aluminium and connected with the 85 annular flanges A² in any appropriate manner.

C' C' are the end covers of the steam-chests, and which may also be of aluminium. The body portion B is intended to contain oil for lubricating the parts it contains, and its cover 90 B' is made capable of ready detachment for enabling access to be had to the interior when required. It will thus be seen that all the working parts of the motor are effectually lubricated and inclosed, so that it will be impossible for dust or other foreign matter to reach said parts.

The aforesaid piston-valves are carried by a hollow rod c³, through which the steam en-

tering the left-hand chest through the pipe c^4 can reach the right-hand chest. The piston-valves act as guides for the hollow valve-rod c^3 and effectually prevent the motive fluid from reaching the interior of the central casting through the tubes a' and becoming mixed with the oil within such casing. The said rod c^3 is provided with an adjustable block c^5 , to which one end of an oscillatory lever d , having its fulcrum at D, is connected. The opposite end of this oscillatory lever is coupled by a link d' to a lever d^2 , which is connected at its upper end d^3 to another link d^4 , which is in turn connected with the free end of an arm d^5 , mounted on a shaft D'. The lower end d^6 of the arm d^2 is connected to an arm d^7 , pivotally connected at d^8 with the piston-rod e of the left-hand piston E. The free end d^9 of this arm d^7 is connected to the end of a link d^{10} , which is pivoted at d^{11} to the body portion B of the motor. The piston-rod e' of the right-hand piston E' is connected to the left-hand piston-rod e at e^2 , and said right-hand piston-rod e' is coupled at f to the crank F' of the shaft F. I attach importance to the fact that the piston-rods overlap at their inner ends and that they are connected together independently of the crank, to which only one of them is directly coupled. This arrangement enables the total length of the motor to be considerably reduced and also facilitates the location of the valve-gear in the comparatively small space provided within the central or body portion of the motor, as aforesaid. The said shaft D' is capable of angular movement by means of the aforesaid adjusting device, which is situated within easy reach of the driver or motor attendant. This device comprises a hand-lever G, fixed to the valve-gear-actuating shaft D' in any appropriate manner to permit of these parts moving together. This hand-lever is provided with a sliding frame g, carrying the screw g' , which by a spring g^2 is normally maintained in engagement with a toothed segment H, stationarily mounted with respect to the said shaft D'. The axle of the said screw g' is furnished with a thumb-piece g^3 for enabling it to be turned in its frame and by so doing to cause it, together with the hand-lever G and the shaft D', to travel in one or other direction in accordance with the direction in which said screw is turned. By this movement a fine adjustment of the valve-gear can be effected. The said hand-lever G is also provided with a pivoted handle G', by which the aforesaid frame g can be shifted away from the toothed segment H, so as to bring said screw g' out of gear with said segment, and thus enable the hand-lever G to be shifted independently of the screw g' when large adjustments of the shaft D' are required. On releasing the hand-lever and the handle G' the said spring g^2 brings the screw g' again into engagement with the segment H, so that fine adjustments can then

be effected through said screw, as before stated. For the purpose of maintaining the said segment H in its stationary position it is formed with a boss h, having lugs h' h' thereon, which are adapted to engage with corresponding recesses in some fixed part of the motor-framing. Mounted on a sleeve h^2 , surrounding said shaft D', is a collar and a nut. This collar and the boss h grip between them the aforesaid motor-framing when said nut h^2 is screwed up, and thus keep the aforesaid lugs h' in firm engagement with their recesses and the segment stationary. By shifting the said hand-lever G into either of its extreme positions the said valve-gear can be so actuated as to alter the position of the valves and permit the steam to drive the motor in a forward or a backward direction, or by moving said hand-lever into intermediate positions by the screw g' the valve-gear can be set to cause any desired cut-off of the steam to be effected and the motor to be driven at the requisite speed in accordance with the amount of work it has to perform. 90

What I claim, and desire to secure by Letters Patent of the United States, is—

1. In a motor, the combination with a pair of coaxially-arranged working cylinders and motive-fluid-distributing valves, of a casing located between said cylinders for completely inclosing the crank and valve operating reversing and expansion gear and having detachable top and side plates, of screw-threaded bosses on said casing for the cylinders to be screwed into, of flanged rings screwed on the outer ends of said cylinders, of motive-fluid chests connected with said flanged rings, and of ported tubes connecting said motive-fluid chests with the casing substantially as described. 105

2. In a motor, the combination with a pair of coaxially-arranged working cylinders and motive-fluid-distributing valves, of a casing located between said cylinders, of screw-threaded bosses on said casing for the cylinders to be screwed into, of flanged rings on the outer ends of said cylinders, of motive-fluid chests connected with said flanged rings, of ported tubes connecting said motive-fluid chests with the casing, of piston-valves working in said tubular and ported tubes, of a hollow rod carrying said piston-valves, and permitting the motive fluid of one chest to reach the other, of means for connecting said rod with the valve-gear inclosed in said casing, of piston-rods hinged to the pistons of the working cylinders and of a length that their inner ends overlap, one of said rods being coupled to the crank, of means for hinging said piston-rods together independently of the crank, of means for connecting the valve-gear to one of the piston-rods, of a crank-shaft extending laterally through one of the side plates of said casing, and of a shaft connected with the valve-gear and extending laterally through the opposite side plate of said 120

casing for enabling the valve-gear to be controlled from the exterior of the casing substantially as described.

3. In a motor, the combination with a pair of coaxially-arranged working cylinders and motive-fluid-distributing valves, of a casing located between and connected with said cylinders for completely inclosing the crank and valve-gear, of piston-rods hinged to the pistons of the working cylinders and of a length that their inner ends overlap, one of said rods being coupled to the crank, of means for hinging said piston-rods together independently of the crank, of means for connecting the valve-gear to one of the piston-rods and of means for controlling said valve-gear from the exterior of the casing substantially as described.

4. The combination, in a motor having a pair of coaxially-arranged working cylinders, motive-fluid-distributing valves and a casing located centrally between and connected with said cylinders; of hinged piston-rods overlapping at their inner ends within said casing and coupled together independently of the crank to which one of them is connected, of valve-gear, and inclosed in the aforesaid casing, of a sliding hollow rod carrying the slide-valves, of motive-fluid chests within which said valves work, of ported tubes connecting said motive-fluid chests with the central casing, of means for connecting the said valve-gear with the said sliding hollow rod, and of means for actuating said gear from the

exterior of the central casing substantially as described.

5. In a motor having a pair of coaxially-arranged working cylinders, motive-fluid-distributing valves and a casing located centrally between and connected with said cylinders; the combination of the hinged piston-rods having overlapping ends coupled together independently of the crank to which one of them is connected, of valve-gear comprising an arm mounted on a transverse shaft extending outside said central casing, a link coupling said arm to one end of a lever whose opposite end is connected with an arm on one of the piston-rods, the free end of which arm is connected by a link to a fixed point, a link coupling said lever to one end of an oscillatory lever whose fulcrum is at a fixed point and whose opposite end is connected to the sliding hollow valve-rod by an adjustable block, of piston-valves mounted at the ends of said hollow valve-rod, of motive-fluid chests, and of ported tubes which connect said motive-fluid chests with the central chamber and within which said piston-valves work, substantially as and for the purpose specified.

In testimony whereof I have hereunto set my hand, in presence of two subscribing witnesses, this 21st day of November, 1901.

FREDERICK LAMPLough.
